CHRISTIAN F. LENG, OF NEW YORK, N. Y.

BOTTLE-VALVE.

1,200,373.

Specification of Letters Patent.

Patented Oct. 3, 1916.

Application filed June 15, 1916. Serial No. 103,765.

To all whom it may concern:

Be it known that I, CHRISTIAN F. LENG, a citizen of the United States, and a resident of the city of New York, borough of 5 Manhattan, in the county and State of New York, have invented a new and Improved Bottle-Valve, of which the following is a full, clear, and exact description.

The object of the invention is to provide 10 a new and improved bottle valve arranged to insure proper working of the valve under all conditions, to permit of conveniently decanting the contents of the bottle, and to prevent refilling of the bottle with spurious 15 goods either by the use of a force pump or like device, or by the use of a vacuum.

Another object is to prevent the valve from being forced down in the bottle neck or being removed therefrom.

In order to accomplish the desired result, 20 use is made of a casing provided at its upper end with an outlet and having interior vertically disposed guide ribs, a flexible valve seat held on the lower end of the casing, and a light hollow valve mounted to slide up and down on the said guide ribs of the casing, the valve having the lower portion of its side curved inwardly and downwardly to fit the said valve seat.

A practical embodiment of the invention 30 is represented in the accompanying drawings forming a part of this invention, in which similar characters of reference indicate corresponding parts in all the views.

Figure 1 is an enlarged sectional side elevation of the bottle valve as applied to the neck of a bottle disposed in upright position; Fig. 2 is a similar view of the same with the parts in position when the bottle 40 is tilted; Fig. 3 is an inverted sectional plan view of the bottle valve on the line 3-3 of Fig. 1; Fig. 4 is an inverted plan view of the valve guide and seat retainer; Fig. 5 is a perspective view of the valve seat; and Fig. 6 is a perspective view of the baffle.

The valve casing is formed of a shell 10, a lining 11 and a baffle 12 intermediate the top 13 of the shell 10 and the top 14 of the lining 11. The shell 10 is provided at the 50 top 13 with a decanting spout 15 adapted to be closed by a cork 16 which, however, is removed prior to the decanting of the contents of the bottle on which the valve casing is used. The top 14 of the lining 11 is provided with a centrally disposed outlet 17 and the interior of the lining is pro-

vided with vertically disposed ribs 18 extending from the lower end of the lining to the top 14, and the upper ends of alternate ribs 18 are provided with extensions 60 19 on the under side of the top 14 and reaching to the wall of the outlet 17, as will be readily understood by reference to Figs. 1, 2 and 3. The ribs 18 and their extensions 19 provide channels or passages for the 65 liquid flowing through the lining to the outlet 17 whenever the bottle is tilted, as indicated in Fig. 2. The baffle 12 is in the form of a disk integral with supporting posts 28 engaging the tops 13 and 14 and 70 the inner face of the shell 10 to support the baffle 12 approximately midway between the outlet 17 and the entrance to the decanting spout 15. In practice, the shell 10, the lining 11 and the baffle 12 are made of 75 porcelain and the parts are assembled prior to burning so that the parts are fused together during the burning process and thereby form a valve casing in which the parts 10, 11 and 12 are firmly fastened together.

The lower end of the lining 11 is a short distance from the lower end of the shell 10 and on the said lower end of the lining 11 abuts the marginal portion of a valve seat 20, 85 preferably made of flexible material such as liquid-proof paper. The valve seat 20 is provided with an inwardly and downwardly extending seating flange 21 and the under side of the valve seat 20 rests on the 90 valve seat retainer and guide 22 provided with a depending portion 23 having an inlet opening 24 and vertically disposed ribs 25 on the wall of the inlet 24.

Within the lining 11 is arranged a valve 95 30, preferably made hollow and of aluminum or other suitable light material, the valve having the lower portion 31 of its side curved inwardly and downwardly to snugly fit the flange 21 of the valve seat 20 100 approximately midway between the curved portion 31 at the time the valve 30 is in normal vertical position. Should the valve 30 be tilted even then the curved portion 31 will make a firm contact with the flange 21 105 to close the valve seat 20 as long as the valve 30 is seated thereon. The valve is provided at its lower end with a depending stem 32 slidingly engaging the ribs 25 to guide the valve in its up and down movement, it being understood that the valve 30 is also 110 guided in its upper portion on the ribs 18.

The body of the valve 30 and its depending stem 32 are preferably formed from one piece of material and the top of the valve 30 is closed by a stopper 33 of cork or other 5 suitable light material. A weight 40 is preferably used in the upper portion of the lining 11 intermediate the top 14 of the lining and the top 33 of the valve 30 to hold the latter normally in position on the valve seat 10. However, this weight 40 may be dispensed with and the distance between the top 33 of the valve and the top 14 of the lining reduced to a minimum.

In attaching the bottle valve to the neck 50 of the bottle use is made of a washer 51, of cork or other material, resting on the top of the neck 50 and forming a seat for the lower end of the shell 10 and the valve retainer and guide 22. The upper end of the neck 50 is provided with an exterior flange 52 and a similar flange 53 is provided exteriorly on the lower end of the shell 10, and the said flanges 52 and 53 are engaged by a band 54 having inturned top and bottom 25 flanges 55 and 56, of which the flange 55 engages the top of the flange 53 and the flange 56 engages the bottom of the flange 52 to securely fasten the bottle valve casing to the neck 50 of the bottle.

The bottle valve shown and described is attached to the neck 50 of the bottle after the latter is filled with the desired liquid, and when the bottle is tilted then the force of the liquid falling down the neck 50 exerts a pressure against the stem 32 of the valve 30 to readily dislodge the stem from its seat to allow the liquid to flow through the opening of the valve seat and through the lining 11 and the outlet opening 17 around the baffle 12 and into and out of the spout 15 into a glass or other suitable receptacle to be filled. When the bottle is returned to normal vertical position the valve 30 immediately returns to closed position on 40 the valve seat 20, and this movement of the valve is aided by the bottle weight 40. It will be noticed that by the arrangement described the valve 30 is firmly held to its seat by its own weight and that of the weight 40 and is not liable to be dislodged either by force or vacuum that may be employed by unauthorized persons for filling the bottle with spurious goods. In case a person attempts to refill an empty bottle 50 with spurious goods by pouring such liquid into the spout 15 then the liquid is gathered by the baffle 12 and flows gently through the opening 17 into the lining 11 in which this liquid acts on the valve 30 to insure its firm seating on the valve seat 20. The entering liquid even tends to right the valve 30 in case it should be tilted, but even then the valve is always firmly seated by its rounded portion 31 engaging the flange 21 of the 60 valve seat. In case pressure or vacuum is

used in attempting to refill the bottle the valve 30 in both instances, on account of its lightness and its peculiar shape and that of the valve seat 20, readily moves to closed position and thereby prevents the inflow of 70 liquid to the bottle.

Having thus described my invention, I claim as new and desire to secure by Letters Patent:—

1. A valve mechanism for bottles, comprising a casing provided at its upper end with an outlet and with vertically disposed interior guide ribs, a valve seat held on the lower end of the casing and made of thin flexible material, a valve retainer and guide fitting against the under side of the marginal portion of the said valve seat, the said retainer and guide being provided with a depending guiding portion, and a light hollow valve mounted to slide up and down on the said guide ribs of the casing, the valve having the lower portion of its side curved inwardly and downwardly to fit the said valve seat, the valve being provided at its lower end with a depending stem guided 90 on the said guide portion.

2. A valve mechanism for bottles, comprising a casing provided at its upper end with an outlet, and interiorly with vertically disposed guide ribs forming passages for the liquid to the outlet, a valve seat held on the lower end of the said casing and provided with a seat flange extending downwardly and inwardly, a valve retainer and guide fitting against the under side of the marginal portion of the said valve seat, the said retainer and guide having a depending guiding portion provided with vertical guiding ribs, and a valve mounted to slide up and down on the guide ribs of the casing 100 and having the lower portion of its side curved inwardly and downwardly and terminating in a depending stem slidingly engaging the ribs of the said valve retainer and guide.

3. A valve mechanism for bottles, comprising a casing provided at its upper end with an outlet, and interiorly with vertically disposed guide ribs forming passages for the liquid to the outlet, a valve seat held 115 on the lower end of the said casing and provided with a seat flange extending downwardly and inwardly, a valve retainer and guide fitting against the under side of the marginal portion of the said valve seat, the 120 said retainer and guide having a depending guiding portion provided with vertical guiding ribs, and a valve mounted to slide up and down on the guiding ribs of the casing and having the lower portion of its side curved inwardly and downwardly and terminating in a depending stem slidingly engaging the ribs of the said valve retainer and guide, the said valve and its stem being 125 hollow and of light material, the stem being 130

closed at the lower end by an integral bottom and the top of the valve being closed by a stopper.

4. A valve mechanism for bottles, comprising a casing provided at its upper end with an outlet, and interiorly with vertically disposed guide ribs forming passages for the liquid to the outlet, a valve seat held on the lower end of the said casing and 10 provided with a seat flange extending downwardly and inwardly, a valve retainer and guide fitting against the under side of the marginal portion of the said valve seat, the

said retainer and guide having a depending guiding portion provided with vertical 15 guide ribs, a valve mounted to slide up and down on the guide ribs of the casing and having the lower portion of its side curved inwardly and downwardly and terminating in a depending stem slidingly engaging the 20 ribs of the said valve retainer and guide, and a weight in the upper portion of the casing and adapted to bear on the top of the said valve.
